UNITED STATES PATENT OFFICE.

JOSEPH M. FISK, OF GREENFIELD, INDIANA, ASSIGNOR OF ONE-HALF TO
W. G. BRIDGES, OF SAME PLACE.

CAR-COUPING.

SPECIFICATION forming part of Letters Patent No. 448,014, dated March 10, 1891.

Application filed July 22, 1890. Serial No. 359,524. (No model.)

To all whom it may concern:

Be it known that I, JOSEPH M. FISK, a citizen of the United States, and a resident of Greenfield, in the county of Hancock and State 5 of Indiana, have invented certain new and useful Improvements in Car-Couplings; and I do hereby declare that the following is a full, clear, and exact description of the invention, which will enable others skilled in the art to 10 which it appertains to make and use the same, reference being had to the accompanying drawings, which form a part of this specification.

My invention relates to improvements in 15 car-couplings which are automatically coupled by the coming together of the cars, thus obviating the necessity of a brakeman or other person going between the cars for such purpose, and thus lessening the liability of injury to such persons.

The object of the invention is to provide a 20 device of the above character which shall be simple and economical in construction, durable in use, and efficient and reliable in operation.

The invention consists in the novel construction and combination of parts hereinafter fully described, and specifically pointed out in the claim.

30 In the accompanying drawings, Figure 1 is a plan view of a car-coupling constructed according to my invention. Fig. 2 is a perspective view of one of the coupling-heads and draw-bars detached.

35 In the said drawings, the reference-numeral 1 designates draw-heads, which may be of any ordinary or suitable construction. These draw-heads are secured to the ends of the cars, and passing through central apertures 40 therein are the round cylindrical draw-bars 2, having nuts or heads 3 at their inner ends, by which they are held in place. At their outer ends these draw-bars are provided with coupling-heads 3', consisting of rectangular blocks

45 having outwardly-projecting hooks 4 at two diagonal corners, the hooks of each draw-head being placed oppositely to each other, so as to interlock when brought together—that is to say, the upper and lower hooks of

50 one draw-bar are placed on the right and left sides of the coupling-head, respectively, while

the corresponding hooks of the other coupling-head are placed on the left and right sides, respectively, of the same, as will readily be understood by reference to the drawings. 55 The ends of these hooks are beveled or curved for a purpose hereinafter explained. The outer faces of the coupling-heads are curved from the inner sides of the hooks to their opposite sides, so as to correspond with the curved 60 ends of the hooks. Intermediate of the end walls 5 of each draw-head is a coiled spring 6, one end of which is secured to the draw-bar and the other end to one of the said end walls, the tendency of the springs being to 65 keep the hooks of the coupling-heads in a horizontal plane.

The numeral 7 designates arms or rods secured to each coupling-head, for the purpose of rotating or turning the same to disengage 70 the hooks for uncoupling.

The operation is as follows: Upon the cars coming together, the beveled or curved ends of the hooks will strike each other, which will slightly rotate the coupling-heads, allowing 75 the hooks to pass each other, when they will assume their normal position by means of the coiled springs and become engaged, thus coupling the cars, as seen in Fig. 2. When it is desired to uncouple the cars, one of the 80 coupling-heads is turned by means of the arm or rod 7 secured thereto, which will cause the hooks to be disengaged, as seen in Fig. 3.

Having thus described my invention, what I claim is—

In a car-coupling, the combination, with a draw-head, of an oscillatory cylindrical bar mounted therein, provided with a square coupling-head having outwardly-projecting hooks with curved ends at two opposite diagonal 90 corners, and having their outer faces curved to correspond with the curved ends of the hooks, a vertical arm or rod for actuating said coupling-head, and a coiled spring encircling the draw-bar, substantially as described. 95

In testimony that I claim the foregoing as my own I have hereunto affixed my signature in presence of two witnesses.

JOSEPH M. FISK.
